CARBON SHEET

Herbert Gordon Scott, Whitestone Landing,
N. Y., assignor to The Egry Register Company,
Dayton, Ohio

Application February 3, 1930. Serial No. 425,692

1 Claim. (Cl. 282—28)

This invention relates to carbon or transfer paper such as used in manifolding work-sheets, and has for one object the provision of paper of the stated character wherein the carbons may be quickly withdrawn or stripped from a pack of finished work-sheets without soiling the fingers.

Another object of the invention is to provide carbon paper with non-soiling finger-holds and with clearances for the corners of work-sheets to be used with the carbons, and wherein the carbons may be inverted so that the useful life thereof is substantially increased.

Another object is to provide carbons of the foregoing type which are capable of being stood on edge with interleaved work-sheets and jogged therewith to more quickly and perfectly bring the carbons into proper alignment with the work-sheets prior to typing, and in which the composite work pack may be satisfactorily introduced either lengthwise or sidewise around the platen of a typewriting machine.

Another object is to provide a carbon having a non-soiling margin of a color contrasting with at least the top work-sheet of a pack, and having means for indicating the position of the work-sheets in a typewriting machine, for instance, the approach of the bottom of the work pack as it advances in typing.

A further object is to provide a carbon of the stated character for use with continuous work forms of the type usually folded in zig-zag formation and torn off in sections along the folds as each of the forms is completed, and in which each carbon of a torn off section presents a non-soiling margin and cut-outs or notches adapted to clear the opposite corners of the forms.

Other objects and advantages of the invention will appear as the description proceeds.

In the accompanying drawing which forms a part of this specification:

Fig. 1 is a plan view of a carbon sheet made in accordance with the invention.

Fig. 2 is a view in perspective of a plurality of worksheets interleaved with carbons embodying my invention, an edge of the top work-sheet being turned up for clarity.

Fig. 3 illustrates another embodiment of my invention in association with a work-sheet.

Fig. 4 is a carbon for use with continuous forms to be progressively torn off with the work sheets in sections after typing.

Fig. 5 shows a carbon of the type shown in

Fig. 4 interleaved with two continuous work webs folded in zig-zag form.

Fig. 6 is a plan view of a torn off work section of the web shown in Fig. 5 prior to stripping the carbons from the forms.

Referring at first to Fig. 1 of the drawing, 60

the numeral 1 indicates generally a carbon sheet embodying my invention. The carbon 1 is cut away preferably at its four corners as at 2

and is provided with a carbonized area 3 so distributed that it leaves a pair of uncarbonized

margins 4 at opposite sides of the sheet, whereby to provide non-soiling finger-holds for ma-

nipulating the carbon in a manner to be explained later. The corners 2 of the carbon 3 70

may be cut off at an angle of approximately 45

degrees as illustrated, or they may be notched in any other suitable way to provide clearances

at the corners 5 of work-sheets 6 as disclosed

in Fig. 2. The carbons 3 are adapted to be ar-

ranged between the work-sheets 6 with one of

the non-soiling margins 4 extending outward

beyond the adjacent edges of the work-sheets

6 as will be readily observed at the left hand side

of the work pack in Fig. 2, the outer edges of 80

the opposite margin 4 being aligned with the other edge of the work-sheets 6. This arrange-

ment provides a substantial clearance at the corners 5. The advantages of the long and

straight margins 4 will be apparent when the 85

work-sheets 6 and the carbons 1 are stood on

edge to jog the sheets into proper alignment

with the carbons prior to typing. After com-

pletion of the typing operation, the composite

pack of work-sheets and carbons is removed 90

from the machine and the exposed margin 4

may be grasped with the forefinger and thumb

of one hand, while one set of the corners 5 of

the work-sheets 6 are grasped likewise with the

other hand, and then with a slight pull of the 95

hands in opposite directions, the carbons 1 are

neatly extracted from the work-sheets 6 without

soiling the fingers. It is also clear that the car-

bons 1 may be inverted to bring into use an un-

worn part of the carbonized area, and that the 100

enclosed one of the margins 4, that is, the one

formerly at the right hand side of the Fig. 2

pack may be exposed for grasping as in the case

of the other margin described. Furthermore,

either of the margins 4 may be extended at 105

either side of the work-sheets depending upon

the preference of the typist or the character of

the work to be done. In some cases it may be

found advantageous to color the margins 4

so as to contrast with the top work-sheet, where-

110

by to facilitate proper grasping of the margins in stripping the carbons from the work-sheets. Also the margins 4 may be provided with means for indicating the position of the work pack in 5 a typewriting machine; for instance, it has been found satisfactory to provide the margins 4 with perforations 7 adjacent the ends of the carbon sheet 1 to indicate approach of the end of the work pack as it advances in typing.

10 In Fig. 3 there is shown a carbon sheet 8 having cut-outs or notches 9 at diagonally opposite corners so as to provide clearances for grasping the corners 10 of a work-sheet 11 assembled with the carbons, it being understood, of course, that a series of such work-sheets 11 and carbons 8 are interleaved to form a composite pack, and that in Fig. 3 one of the work-sheets has been removed to more clearly illustrate the general arrangement of the carbons with respect 15 to the work-sheets. It will be noted that the carbon sheet 8 includes uncarbonized margins 12 extending substantially the full length of the carbon at opposite sides thereof between the cut-outs 9 and the other end of the carbon. Therefore the carbons 8 may be jogged on edge with the interleaved work-sheets in the same manner as in the Fig. 1 example of the invention, which is an appreciable advantage in combination with the other novel features. The Fig. 3 carbon 20 is also invertible and the margins may be extended at either side of the work-sheets by shifting to the right or the left. It will be seen that the work-sheets and carbons may be inserted around the platen of a typewriting machine with facility. The long margins of this 25 invention are also to be distinguished from the short tabs heretofore employed, and wherein the tabs had a tendency to curl and become otherwise troublesome in assembling the work pack and handling the same in a typewriter. Indicators in the form of perforations 13 or otherwise may be provided in the margins for the 30 purpose already explained.

For adapting the carbon for use with continuous work webs which the generally folded in zig-zag formation and torn off in sections along the folds after typing, a carbon sheet 14 (Fig. 4) is provided with a carbonized area 15, an uncarbonized continuous margin 16 disposed 35 along one edge of the sheet 14, and a series of recurrent notches or cutouts 17 arranged to intersect lines of detachment 18 of the carbon 14. Heretofore it has been the practice to cut off one 40 of the corners of the forms to permit the car-

bons to project for grasping, but this is objectionable in that the forms present a mutilated appearance due to the cut corners and for that reason are not entirely satisfactory. By using the carbons of my invention all four corners of the forms remain intact and the appearance of the forms consequently meets the approval of the most critical. In Fig. 5 there is disclosed for illustration two work webs 19 having a carbon of the Fig. 4 type interleaved therewith and folded in zig-zag formation so that the forms 20 comprising the webs may be severed in complete sections along the folds after typing. Fig. 6 shows one of such form sections 20 after detachment from the webs 19. It will be observed that the uncarbonized margin 16 extends outward beyond the adjacent edge of the forms 20, and that the cut-outs 17 provide clearances at the two corners 21 of the forms 20 opposite to the margins 16, so that by grasping the margin 16 and either of the corners 21 the carbons may be easily stripped from the forms 20 by pulling in opposite directions. It is obvious that the work webs 19 may be of any number and interleaved with the necessary carbons 14 to transfer 50 the type impressions to all of the webs. In the interest of clearness I have illustrated only two webs and one carbon, but it is evident that the principle is the same irrespective of the number of webs and carbons used to make up a work pack. Where it is desirable to indicate approach of the bottom of a form 20, perforations or other suitable indicating means may be carried by the margin 16. Also, the margins 12 of Fig. 3, and the margins 16 of Fig. 4 may be 55 colored to contrast with the top work-sheet.

In conclusion it is to be understood that while the illustrated examples represent practical embodiments of the invention, it is not to be construed as limited to the exact details set forth, 60 since, manifestly, the same may be varied without departing from the spirit of the invention as defined in the appended claim:

I claim:

The combination with a work sheet of a carbon paper having its four corners cut away to provide clearance at the corners of the work sheet, said carbon paper having two uncarbonized margins oppositely disposed between the cut corners, the sum of the widths of the carbonized portion of the carbon paper and one of the uncarbonized margins being substantially equal to the width of the work sheet.
